UNITED STATES PATENT OFFICE

2,460,930

FASTENER ATTACHING MACHINE

Sylvester L. Gookin, Quincy, Mass., assignor to
United Shoe Machinery Corporation, Flemington, N. J., a corporation of New Jersey

Application May 3, 1946, Serial No. 666,991

10 Claims. (Cl. 218—14)

1 The purpose of the present invention is to provide improvements in machines for attaching fasteners to sheet material, and more especially tubular fasteners through which pointed spindles may extend to pierce holes in the sheet material for the reception of the tubular portions of the fasteners. The problem to which the invention is primarily related is to provide a power-operated machine for doing such work more rapidly than it can be done with hand implements of the type set forth in United States Letters Patent No. 2,422,405, granted June 17, 1947 in my name.

The aforesaid copending application discloses a typical example of work in which six small individual eyelets are used to connect a grommet and a washer in process of being attached thereby to a heavy canvas product such as a tarpaulin. The same type of work is illustrated herein, but in this disclosure the tubular fasteners corresponding to the six small eyelets are all integral portions of a grommet instead of individual elements, as formerly represented. The integral construction is not essential to the present invention, although it is preferable because it saves much time in handling and assembling the component parts of such a grommet and washer combination.

The novel features embodying the invention and hereinafter set forth are useful for installing fasteners singly, with or without washers, as well as for gang eyeleting with or without washers. Therefore, to state the principles of the invention in their simplest terms, certain features thereof will first be described with regard to just one tubular fastener such as an eyelet.

A machine embodying the invention as herein illustrated includes an anvil on which an eyelet may stand on end. The anvil is provided with a pointed spindle to localize the eyelet and pierce the eyelet-receiving material, if necessary. The spindle is telescopically related to the anvil to be depressed by an eyelet-setting tool, but is normally raised by a spring and periodically locked in its upper position where its point will extend above the barrel of the eyelet to pierce the material while the latter is being pressed down.

A ram is arranged above the anvil to depress the material along the barrel of an eyelet and to carry an eyelet-setting tool, but the latter is movably related to the ram to be shifted to and from its potential fastener-engaging position. The eyelet-setting tool and the spindle-locking means are interconnected by a mechanism that puts each out of operation when the other is brought into operation.

2 The machine is provided with power-driven means for reciprocating the ram. Alternate down-strokes of the ram may be used to depress the eyelet-receiving material, and the intervening down-strokes may be used to upset and clinch eyelets. Preferably, the locking and unlocking of the spindle, and the shifting of the eyelet-setting tool to and from its potential eyelet-engaging position will be accomplished automatically by mechanism activated by an element of the aforesaid power-driven means at a cyclic rate one-half that of the ram. Accordingly, one complete operating cycle of the machine will include two cycles of reciprocation of the ram, in the first of which a presser, also carried by the ram, will impale the eyelet-receiving material on an eyelet, and in the second of which the eyelet will be clenched by an upsetting tool.

Referring to the drawings,

Fig. 1 is a perspective view of a machine embodying the invention and equipped with means for installing a grommet having six small eyelet barrels;

Fig. 2 is a front elevation of the tool portion of the machine;

Fig. 3 is a top plan view of the bed and anvil assemblage;

Fig. 4 is a perspective view of a work-indexing pin with which the anvil is provided;

Fig. 5 is a perspective view, on a relatively large scale, of a grommet and washer;

Fig. 6 is a left side elevation of the assemblage included in Fig. 2;

Fig. 7 is a view similar to Fig. 6 but showing the eyelet-setting tools in register with the anvil;

Fig. 8 is a vertical section, on a relatively large scale, of a grommet-and-washer assemblage in the final stage of being installed;

Fig. 9 is a vertical cross-section of the half-speed cam assemblage for shifting the tool-carrier (see line IX—IX in Fig. 10);

Fig. 10 is a vertical section in a plane at right-angles to that of Fig. 9 (see line X—X in Fig. 9);

Fig. 11 is a vertical section, viewed as in Fig. 6, of the telescopic connection by which the upper and lower slides are coupled;

Fig. 12 is a right side elevation including the ram, a crank motion for reciprocating it, and means for driving the half-speed cam;

Fig. 13 is a front elevation of a one-revolution clutch assemblage;

Fig. 14 is a vertical section of the anvil assemblage, and a work-piece about to be impaled on a grommet; and

Fig. 15 is a view similar to Fig. 14 but showing a

grommet-and-washer assemblage about to undergo the upsetting operation in the second revolution of a work cycle.

The frame 10 of the machine is provided with a horizontal bed 11 for supporting a fixed anvil 12 and a lower slide 13, the latter being movable to the front and rear and embedded in a groove in the bed. The purpose of the lower slide is to lock and unlock the pointed spindles 14 that normally project upwardly from the anvil to localize the eyelet barrels of the grommet, and to pierce the eyelet-receiving material through which those barrels are to extend.

An upper slide 15, hereinafter termed "tool carrier," is likewise movable to the front and rear. Its purpose is to carry a work-presser 16 and a group of setting tools affixed to a block 17. The tool-carrier 15 has dovetail connection with a block 18 which constitutes a part of a vertically movable ram 19. The two slides 13 and 15 are connected by a vertical coupling pin 20 which (see Fig. 11) is anchored to the lower slide and has telescopic engagement with the upper slide. This pin synchronizes and equalizes the horizontal movements of the slides but permits the upper slide to move up and down.

The ram 19 slides in vertical ways in the frame 10 and derives its reciprocation from a crank 21 (Fig. 12) to which it is connected by a link 22 and a wrist-pin 23. The crank 21 is carried by a power-driven shaft 24 journaled in the frame and provided with a one-revolution clutch hereinafter described.

A grommet of the type herein shown (Figs. 5 and 8) is made of one circular piece of ductile sheet metal the central zone of which is drawn to provide a barrel portion 25 projecting from an annular clamping plate or flange 26. Six portions of the flange are drawn to provide relatively small eyelet barrels 27, and these are symmetrically related to the barrel portion 25 and to one another. The same pattern is embodied in the arrangement of a larger central hole 28 and six small holes 29 in a washer 30 adapted to be assembled with the grommet. The barrel portions of the grommet are long enough to extend through four plies of canvas and through the washer and to provide enough additional length to be upset and clenched on the outer face of the washer, as shown in Fig. 8.

The same pattern is embodied in the arrangement of a central indexing pin 31 (Figs. 3 and 4) and six spindles 14 each telescopically related to the anvil 12. The pin 31 is normally upheld by a compression spring 32 (Fig. 8), and the spindles by light springs 33. When a grommet is seated on the anvil the pin 31 projects through and above the barrel 25, and the points of the spindles 14 project through and above the small barrels 27 (Fig. 14). A slot 34 (Fig. 4) in the pin 31 receives a retaining pin 35 installed in the anvil. The retaining pin permits the indexing pin to be depressed, but arrests its upward movement while the spring 32 is under compression. The lower ends of the pointed spindles 14 are all arranged to abut the upper face of the locking slide 13 when the latter is in its forward position (Fig. 6) but not when it is in its rear position (Fig. 7), at which time the spindles may be depressed. By means hereinafter described, the slide 13 is shifted intermittently to and from its locking position.

The work-presser 16 (Fig. 6) is provided with a flat work-engaging face, a central socket 36 large and deep enough to receive a grommet bar-

rel 25 and the projecting end of the indexing pin 31, and with six small holes 37 adapted to receive the eyelet barrels 27 without fouling the pointed spindles 14.

The tool block 17 is provided with a group of six small setting tools each having an upsetting shoulder 39, and with a large central setting tool having an upsetting shoulder 40. These tools are arranged to operate simultaneously on the barrels 27 and 25 to clench them as shown in Fig. 8.

The motion for shifting the slides 13 and 15 to front and rear is derived from the shaft 24 through the medium of an internal spur gear 41 (Figs. 9 and 10) having an external cam surface 42. This gear and cam member surrounds a concentric collar 43 keyed to the shaft, and has a bearing on the collar. A spur pinion 44, formed on the collar, engages and drives an intermediate gear 45 in mesh with the internal gear 41. The cam 42 is thus driven at a rate exactly one-half that of the shaft. The intermediate gear 45 turns on a fixed pintle 46 pressed tightly into a bracket 47 having one bore engaging the shaft 24 and another engaging a fixed pin 48.

The cam 42 engages a roll 49 carried by an arm 50 arranged to be oscillated about the pin 48 on which the arm has a bearing. A tension spring 51 connected to the arm maintains the roll 49 against the cam. A link 52 connects the lower end of the arm 50 and one arm 53 of a bell-crank which also has a pair of arms 54 bridged by a pivot pin 55 (Fig. 11). A forked link 56 connects the pin 55 and the coupling pin 20. The hub of the bell-crank 53, 54, 55 is mounted on a fulcrum stud 57 affixed to the bed (Fig. 6).

The cam 42 (Fig. 9) has a high concentric segment and a low concentric segment diametrically opposite each other. The initial position of the cam is shown in this view. The low segment places the work-presser 16 in register with the anvil and keeps it in that position throughout the first down-stroke and a portion of the first up-stroke of each four-stroke cycle, and the high segment places the group of setting tools in register with the anvil and keeps it in that position throughout the second down-stroke and a portion of the second up-stroke of the cycle.

A one-revolution clutch for driving the shaft 24 is represented in Figs. 1 and 13. It is a clutch of the rocker key type and its mode of operation is set forth in United States Letters Patent No. 784,653, granted March 14, 1905, in the name of O. S. Beyer. The clutch comprises a driven member 60 keyed to the shaft, a driving member 61 loosely mounted on the shaft, and a rocker key having a shank 62 and a head 63. The driving member is a pulley (Fig. 1) to be rotated continuously by a belt (not shown). A cylindrical portion of the shank 62 has a bearing in the driven member, but a semicylindrical portion thereof is arranged to be rocked into and out of a semicylindrical recess in an interior wall of the driving member. A spring follower 64 located in a bore 65 in the driven member engages the head 63 and normally rocks the key to its driving position, but when the head is against a shoulder 66 of the driven member the latter is declutched.

The one-revolution control comprises a stop 66, a latch 67 carried thereby, a bell-crank 68 and a pin 69 carried by the latter. The stop 66 and the bell-crank are both mounted on a fixed pivot stud 70 and the former is normally drawn into the path of rotation of the head 63 by a tension spring 71. When the head 63 is carried against

the upper end of the stop by rotation of the driven member, the first effect is to rock the key to its declutching position, and the final effect is to arrest rotation of the driven member when the shoulder 65 strikes the head. The latch 67 is mounted on a pivot pin 72 affixed to the stop, and is provided with a shoulder 73 arranged to latch the pin 69. The latch is normally drawn to its latching position by a spring 74. A rod 75 connected to the bell-crank may extend to a clutch-treadle (not shown).

When the rod 75 is depressed, the bell-crank shifts the pin 69, the latch 67 and the stop 66 to the right, thereby releasing the rocker key. Now, the spring follower 64 will rock the key to its clutching position when the key recess in the driving member permits. When the driven member has rotated about $\frac{1}{4}$ revolution a cam portion 76 thereof rocks the latch 67 about its pivot 72 and thereby trips the latch to release it from the pin 69. Consequently, even though the rod 75 may remain depressed, the spring 71 will return the stop 66 to the path of the head 63 and thereby arrest the driven member at the conclusion of one revolution. The operator must raise the rod 75 or permit a spring to raise it to re-engage the pin 69 and the latch shoulder 73.

To install grommets and washers in a work-piece, the operator will first punch one hole in each selected area of the latter, if the holes have not already been provided. The holes should be about the same size as the indexing pin 31 in the center of the anvil, but no larger. After placing a grommet on the indexing pin and pointed spindles of the anvil (Fig. 14), the operator will place a selected area of a work-piece 100 on the points of the spindles, so that the indexing pin will project through the hole in that area. Now, if the half-speed cam 42 is in its initial position (Fig. 9), the work-presser 16 will be in register with the anvil, and the pointed spindles will be locked by the slide 13. The first revolution of the shaft 24, due to tripping the clutch, will rotate crank 21 (Fig. 12) through one revolution and this will depress and raise the ram 19 and, through action of the high spot of cam 42, will rock arm 59 (Fig. 9) and thus will distend the spring 51 and shift both slides 13 and 15 to the rear during the latter stages of the up-stroke of the ram. The work-piece, having been impaled on the barrels of the grommet by the work-presser, is now ready to receive a washer 30, which the operator will place by hand before again tripping the clutch. At this stage the setting tools in the block 17 will be in register with the anvil, and the pointed spindles 14 will be unlocked. Consequently, the next down-stroke of the ram will complete the installation of the grommet as represented in Fig. 8 which illustrates the spindles and the indexing pin 31 depressed by the pilots of the setting tools. During the latter stages of the next up-stroke of the ram the cam 42 will permit the spring 51 to contract and thus permit the spring to act to shift the slides 13 and 15 to their forward positions, thereby locking the pointed spindles and returning the work-presser to its path of operation in readiness for the next cycle of operations.

Having described my invention, what I claim as new and desire to secure by Letters Patent of the United States is:

1. A fastener-attaching machine comprising a fastener-supporting anvil, a ram movable up and down, a tool-carrier mounted on the ram and shiftable relatively thereto, a work-engaging

presser and a fastener-setting tool both carried by said tool-carrier, power-driven means arranged to reciprocate the ram up and down, and mechanism operable by said power-driven means for causing said presser and said fastener-setting tool to cooperate alternately with the anvil at a cyclic rate one-half that of the ram, said presser being adapted to impale a work-piece on a fastener seated on the anvil.

2. A fastener-attaching machine comprising a fixed anvil for supporting a tubular fastener standing on end, a ram movable up and down, a horizontally movable tool-carrier mounted on the ram, a work-engaging presser and a fastener-setting tool both carried by said tool-carrier, power-driven means arranged to reciprocate the ram up and down, and mechanism operable by said power-driven means for shifting said tool-carrier to place the presser in cooperative relation to the anvil during alternate down-strokes of the ram and to place the fastener-setting tool in cooperative relation to the anvil during the intervening down-strokes of the ram, the presser being adapted to impale a work-piece on a fastener on the anvil.

3. A fastener-attaching machine comprising a fastener-supporting anvil, a ram movable up and down, a tool-carrier mounted on the ram and shiftable relatively thereto, a work-engaging presser and a fastener-setting tool both carried by said tool-carrier, a power-driven shaft, a cam loosely mounted thereon, gearing driven by the shaft for rotating the cam at one-half the cyclic rate of the shaft, means carried by the shaft for reciprocating said ram, and mechanism operable by said cam for shifting said tool-carrier in one direction in alternate cycles of the ram and in the opposite direction in the intervening cycles of the ram and thereby to cause the presser and the fastener-setting tool to cooperate alternately with said anvil.

4. A fastener-attaching machine comprising an anvil, a pointed spindle telescopically related thereto, a spring by which the spindle is normally upheld, a ram arranged to travel up and down, power-operated means by which the ram is actuated, mechanism actuated by an element of said power-operated means for locking said spindle during the alternate cycles of the ram and unlocking the spindle during the intervening cycles thereof, and a presser carried up and down by the ram and adapted to depress a work-piece along the spindle when the spindle is locked.

5. A fastener-attaching machine comprising an anvil, a pointed spindle telescopically related thereto, a spring by which the spindle is normally upheld, a ram arranged to travel up and down, power-operated means by which the ram is actuated, a tool-carrier supported by said ram but shiftable relatively thereto, a work-engaging presser and a fastener-setting tool both carried by said tool-carrier, mechanism actuated by an element of said means for shifting said tool-carrier to place the presser in register with the anvil in alternate cycles of the ram and to place the fastener-setting tool in register with the anvil in the intervening cycles of the ram, and means also operable by an element of said power-driven means for locking and unlocking the spindle according to the aforesaid placing of the presser and the fastener-setting tool.

6. A fastener-attaching machine comprising an anvil, a pointed spindle telescopically related thereto, a spring by which the spindle is normally

upheld, a ram arranged to travel up and down, power-operated means by which the ram is actuated, mechanism actuated by an element of said means for locking said spindle during alternate cycles of the ram and unlocking the spindle during the intervening cycles thereof, a presser carried up and down by the ram and adapted to depress a work-piece along the spindle when the spindle is locked, and a fastener-setting tool also carried up and down by the ram and adapted to upset a fastener on the anvil when the spindle is unlocked, the presser and the fastener-setting tool being shiftable laterally to and from an operating path in register with the anvil.

7. A fastener-attaching machine comprising an anvil, a pointed spindle telescopically related thereto, a spring by which the spindle is normally upheld, a power-operated ram arranged to travel up and down, means adapted to lock and unlock the spindle, a presser carried up and down by the ram and adapted to depress a work-piece along the spindle when the spindle is locked, a fastener-setting tool also carried up and down by the ram and adapted to upset a fastener on the anvil when the spindle is unlocked, the presser and the fastener-setting tool being shiftable laterally to and from an operating path in register with the anvil, and means by which the locking means and the presser are coupled to insure locking the spindle when the presser is in said operating path and unlocking the spindle when the presser is displaced from said path.

8. A fastener-attaching machine comprising a fastener-supporting anvil provided with a group of pointed spindles telescopically related thereto, the spindles being normally upheld by springs, a locking member common to all said spindles, power-driven means by which a tool-carrier is moved toward and from the anvil, a work-presser and a group of fastener-setting tools carried by the tool-carrier, and connections actuated by an element of said power-driven means for operating said locking member to lock and unlock the spindles and for shifting said work-presser and said group of tools alternately to and from an operating path in register with the anvil.

9. A fastener-attaching machine comprising a fixed bed, a fastener-supporting anvil thereon, the anvil having a group of pointed spindles tele-

scopically related thereto, the spindles being normally upheld by springs, a ram located above said bed and movable toward and from the latter, power-driven means by which the ram is moved, 5 a tool-slide carried by the ram, a locking slide movably arranged on the bed, coupling means connecting said slides to maintain them in co-ordinated relation, the locking slide being arranged to lock and unlock the spindles, a work-presser carried by the tool-slide and arranged to cooperate with the anvil when the spindles are locked, a group of fastener-setting tools also carried by the tool-slide and arranged to cooperate with the anvil when the spindles are unlocked, 10 and mechanism actuated by an element of said power-driven means for shifting said slides to and fro in timed relation to the strokes of said ram.

10. A fastener attaching machine comprising an anvil, a pointed spindle telescopically related thereto, a spring by which the spindle is normally upheld, a ram movable up and down above the anvil, a tool-carrier carried by the ram but movable relatively thereto, a work-presser and a fastener-setting tool both carried by said tool-carrier, a one-revolution clutch, a shaft driven thereby, means connecting said shaft and the ram for imparting one cycle of reciprocation to the ram for each revolution of the shaft, means operable by said shaft for shifting said tool-carrier in one direction during alternate revolutions of the shaft, means for shifting said tool carrier in the opposite direction during the intervening revolutions thereof, and means operable by said shaft for locking and unlocking said spindle in timed relation to the shifting of said tool-carrier.
